UNITED STATES PATENT OFFICE.

EDWARD J. WEEKS, OF NEW YORK, N. Y., ASSIGNEE OF FORTY PER CENT.
TO J. VEIT, OF NEW YORK, N. Y.

ROTARY GAS-ENGINE.

No. 838,150.

Specification of Letters Patent.

Patented Dec. 11, 1906.

Application filed February 2, 1906. Serial No. 299,223.

To all whom it may concern:

Be it known that I, EDWARD J. WEEKS, a citizen of the United States, residing at New York, in the county of New York and State 5 of New York, have invented certain new and useful Improvements in Rotary Gas-Engines, of which the following is a specification.

This invention relates to rotary engines of the type embodying abutment and driving 10 pistons actuated in alternation by a step-by-step movement, and aims to improve the construction whereby an explosive medium may be advantageously used as the motive agent.

15. The invention consists of the novel features and structural details which hereinafter will be more fully disclosed and claimed.

In the accompanying drawings, forming a 20 part of the specification, Figure 1 is a vertical longitudinal section of an engine embodying the invention on the line X X of Fig. 2 looking to the right, as indicated by the arrows. Fig. 2 is a section on the line Y Y of Fig. 1, showing the position of the pistons 25 when receiving a charge of explosive motive medium therebetween. Fig. 3 is a view similar to Fig. 2, showing the driving-pistons an instant after the explosion has taken place. Fig. 4 is a sectional detail showing the parts 30 on a larger scale. Fig. 5 is a detail perspective view of a piston-ring, showing a clutch element opposite one of the pistons.

Corresponding and like parts are referred to in the following description and indicated 35 in all the views of the drawings by the same reference characters.

In its organization the engine comprises the shaft 1, hub 2, cylinder 3, and pistons 4 and 5. It is contemplated to impart movement to either the hub or cylinder, and, as shown, the latter is stationary and the hub rotatable. The power may be taken from the engine-shaft 1 either by means of a drive-belt (not shown) applied to the band-pulley 6' or by means of a translator (not shown) in mesh with the gear-wheel 7'. The motive medium may be introduced between the pistons from any convenient point, according to the construction of the engine, 45 and, as shown, the cylinder or casing is composed of hollow walls subdivided into compartments or spaces 8 and 9, the former being connected with the source of supply and the latter with the exhaust-pipe. Inlet-

ports 10 and outlet-ports 11 are provided in 55 the inner wall of the cylinder adjacent to the partitions.

The compartments 8 are in communication with one another and with the inlet A, which is connected in the usual way with a source of 60 supply for the motive medium. The compartments 9 are also connected with one another, preferably by means of the annular chamber C, and with the exhaust B, which leads from the chamber C. 65

The pistons 4 and 5 stand in the relation of abutment and driving elements, since one is stationary while the other is traveling, and vice versa. These pistons are connected to rings 6 and 7 and may be provided in any 70 number, according to the size and capacity of the engine. Clutch elements are provided for alternately connecting the pistons to, respectively, the hub and cylinder, and means are employed for shifting the clutch elements 75 at the proper time, so as to disconnect the pistons from the hub and to connect them with the cylinder, and vice versa.

The clutch elements may be conveniently located and are preferably applied to the 80 pistons which are best adapted to receive the same. As indicated, the clutch elements 12 are slidably mounted in openings or seats of the pistons and are adapted to enter grooves or seats 13 in the opposing walls of 85 the space formed between the hub and cylinder. Shifting-springs 14 coöperate with the clutch elements for actuation thereof and are preferably bowed and have their ends in engagement with tappets 15, normally projected beyond opposite faces of the pistons, 90 so as to be pressed upon when the pistons come together for increasing the curvature of the springs, whereby the clutch elements are reversed—that is, disconnected from one 95 part, as the hub, and engaged with the other part, as the cylinder. The shifting or actuating springs 14 may be replaced by any mechanism for attaining the desired end—namely, to effect a reverse movement of the 100 clutch elements. A pocket or space is formed between adjacent pistons to receive a charge of motive medium, and this space or pocket may be provided in any determinate way. As shown, depressions 16 are 105 formed in the faces of the pistons. As shown in Fig. 2, the pistons 4 and 5 have come together and the pocket between them is in

register with the inlet-port 10, and the exhaust-port 11 is closed by the piston 4. After the charge of explosive medium has been received in the pocket or space between the 5 pistons the latter travel a short distance to admit of the piston 4 uncovering the exhaust-port 11 and to cover the inlet-port 10, and the instant this has been accomplished the piston 4 becomes clutched to the cylinder and constitutes the abutment. A moment later the explosive medium is ignited, and the resultant expansion of the gases drives the piston 5 forward. When the piston 5 reaches the next piston 4 in advance 10 thereof, the operation just described is repeated, the piston 5 becoming the abutment and the piston 4 the driver, and so on in alternation.

The explosive charge is ignited by any means 20 commonly employed in engines of the explosive type, and, as illustrated, an electric spark 25 er 17 of any structural type is employed and is connected by wires with the battery or generator (not shown) employed 30 for supplying the electric current. It is to be understood that any approved mechanism is to be employed for producing the spark at the proper time. The sparking plug extends across the space formed between the walls of the cylinder and is threaded into the same.

For starting the engine, pipes 18 extend across the space formed between the walls of the shells of the cylinder and are in communication 35 with an air-compressor (not shown) or other source of supply of fluid motive medium. These pipes are approximately in line with the sparking devices, so as to admit the fluid medium into the pockets between the pistons at the beginning of the 40 stroke. Valves 19 are seated in the pipes 18 to prevent the escape of pressure due to the explosive. After the engine has been started the fluid medium is cut off from the pipes 18, 45 thereby permitting the engine to be run by explosion of the gaseous mixture or like combustible motive medium.

Within the purview of the invention it is contemplated to embody the invention in a 50 reversible rotary engine, it being necessary only to provide duplicate sparking devices and starting mechanism at each side of the partitions subdividing the space formed between the inner and outer walls of the cylinder and to provide means for admitting the 55 gaseous mixture into one or the other of the spaces 8 and 9. The engine is of such construction as to admit of the utilization of steam, compressed air, or other fluid me-

dium as the motive agent, in which case the 60 sparking devices will be dispensed with and the explosive medium substituted by the selected motive agent, such as steam, compressed air, and the like. In this construction the engine may comprise any number of 65 pairs of piston-rings and pistons, two such pairs being illustrated, and ball-bearings being interposed between the piston-rings and between the piston-rings and the heads of the cylinder, so as to minimize the friction. 70

The engine is started by admitting fluid medium to the pistons by means of the pipes 18, and after it has acquired sufficient momentum to operate by explosion of the gaseous mixture or like motive agent the starting medium is cut off. As the moving or driving pistons reach the limit of their stroke they receive between them and the abutment-pistons a charge of the explosive medium, which is exploded a moment later 80 after the inlet-ports have become closed, and the driving-pistons change position with the abutment-pistons. When the driving-pistons impact against the abutment-pistons, the clutch-shifting mechanisms are actuated 85 and the clutches reversed, the moving piston becoming stationary and the stationary piston acting as the driver and receiving the force of the motive agent, so as to operate the engine. In the event of the motive agent 90 being a gaseous mixture, such as commonly employed in explosive-engines, the elements are mixed, and the mixture compresses preliminary to supplying the same to the engine. Hence the charge admitted into the 95 space or pockets between the pistons is properly condensed, so that when exploded the best results possible are attained.

Having thus described the invention, what is claimed as new is—

An explosive rotary engine comprising a hub, cylinder, pistons arranged to travel in the space formed between the hub and cylinder and having depressions or recesses in their faces to form pockets for the reception 105 of the explosive medium, clutches co-operating with the pistons for alternately connecting them to the hub and cylinder, means for supplying a charge of explosive motive agent to the pockets, and means for igniting the 110 charge, substantially as set forth.

In testimony whereof I affix my signature in presence of two witnesses.
